R. R. JACKSON.
MANUALLY OPERATED INFLATING PUMP.
APPLICATION FILED SEPT. 5, 1916.
1,254,231. Patented Jan. 22, 1918.

INVENTOR
ROBERT R. JACKSON
By *Robert R. Jackson*

UNITED STATES PATENT OFFICE.

ROBERT REYNOLD JACKSON, OF SOUTH KENSINGTON, LONDON, ENGLAND.

MANUALLY-OPERATED INFLATING-PUMP.

1,254,231.

Specification of Letters Patent. Patented Jan. 22, 1918.

Application filed September 5, 1916. Serial No. 118,510.

To all whom it may concern:

Be it known that I, ROBERT REYNOLD JACKSON, a subject of the King of Great Britain and Ireland, and resident of South 5 Kensington, county of London, England, have invented a certain new and useful Improvement in Manually-Operated Inflating-Pumps, of which the following is a specification.

10 This invention relates to tire and like inflators of the reciprocating barrel type, and the present invention consists essentially in the provision of an operating foot step at the foot end of the barrel so that the inflator 15 can be worked by the conjoint action of hand and foot, said operating foot step being rigid with the barrel or foldable; other features consist in the provision of the hereininafter described means for locking the barrel 20 and plunger together for the purpose hereinafter set forth, and in making the barrel of great length to enable the user to stand upright when pumping; said barrel being in one length or in sections.

25 The invention is illustrated by the accompanying sheet of drawings, in which:—

Figures 1 and 2 are views taken at right angles to each other of an inflator with barrel formed in one length, Fig. 2 being partly 30 in section.

Figs. 3 and 4 are views of an inflator with barrel provided with an outer sheath, Fig. 3 being the closed in position and Fig. 4 the expanded position.

35 Like letters of reference indicate corresponding parts in the several figures.

In carrying out the invention, the inflator or pump, which is of the type in which the barrel *a* is the reciprocated part, is made 40 in one piece and extremely long—Figs. 1 and 2—to reach from the ground to about the user's shoulder, thus enabling him to stand upright when pumping, the base *b* of the plunger *c*, which is also correspondingly 45 long, being provided with any usual or suitable form of foot *d* and nipple *e* for connecting up.

The foot end *f* of the barrel *a* is provided 50 with an operating foot step *g* which may be either rigid with said barrel or foldable, so that when extra pressure is required when working, the user's foot can be placed thereon and the pump worked by hand and foot pressure at the same time.

55 Owing to the great length of the pump

barrel and the conjoint action of hand and foot there obtains a great reduction in fatigue to the user, and, as the pump is intended not only for garage use but also for owner-drivers and others, the barrel of the 60 pump may be made in sections instead of in one length, that is to say, the barrel *a*, shown in Figs. 1 and 2 of the drawings, would, as shown in Figs. 3 and 4, be made shorter and be provided with an outer sheath *a'* of approximately the same length as said barrel *a*, which sheath *a'* when the pump is required for use is slid to the top end of said barrel *a*, as in Fig. 4, making the barrel of a length corresponding to that of the barrel 65 *a*—Fig. 1—said sheath being locked to said barrel by any suitable means, and when not required is unlocked and pushed down over the barrel—as in Fig. 3—and again locked thereto, thus decreasing the length of 70 said pump, enabling the same to be readily carried about.

Further, owing to the extreme length of the pump or inflator it is preferable that the barrel be, when the same is in one piece or 80 length, stayed, ribbed or otherwise protected to prevent denting or buckling.

To prevent the pump or inflator opening out when being carried about, the foot step *g* of the barrel *a* is provided with a heel or 85 projection *i* adapted when said barrel is depressed against the action of the spring *h* and turned around as in Fig. 1 to engage under the action of said spring *h* in a recess *j* in the underside of the head of the base *b* 90 of the plunger *c*, thus locking the barrel and plunger together.

By my invention I dispense with any exterior handles so that the apparatus forms 95 practically a pole pump.

Having now described my invention, what I claim as new and desire to secure by Letters Patent of the United States is:—

1. A tire inflating pump including a stationary plunger and a reciprocating barrel 100 of extended length whereby the upper end thereof constitutes a handle for the operator when standing upright, and an offset stirrup at the lower end of said barrel whereby the latter may be operated by the conjoint use 105 of hand and foot.

2. A tire inflating pump including a stationary plunger, a reciprocating barrel, a tubular sheath extensibly fitted to the upper end of said barrel to provide an operator's 110

hand grip, and a laterally projecting foot stirrup carried by the lower end of the barrel.

3. An inflator comprising a stationary plunger, a reciprocating barrel of great length, a foot step at the foot end of said barrel, a heel to said foot step, a spring interposed between said foot step and the head of the base of the plunger, and a recess on

the underside of said head, said heel engaging in said recess when the barrel is turned around after compressing said spring. 10

In testimony whereof I have affixed my signature in presence of two witnesses.

ROBERT REYNOLD JACKSON.

Witnesses:

ROBT. HUNTER,
PERCY M. GOODWIN.
